RAILWAY CAR

Filed Oct. 20, 1926

INVENTOR
Andrew Christianson
By Archibald Martin,
Attorney

UNITED STATES PATENT OFFICE.

ANDREW CHRISTIANSON, OF BUTLER, PENNSYLVANIA, ASSIGNOR TO STANDARD STEEL CAR COMPANY, OF PITTSBURGH, PENNSYLVANIA, A CORPORATION OF PENNSYLVANIA.

RAILWAY CAR.

Application filed October 20, 1926. Serial No. 142,920.

My invention relates to railway cars, and particularly to passenger cars, and window structures therefor.

My invention has for one of its objects, the provision of an improved arrangement, whereby window frames may be more conveniently and cheaply mounted in the sides of the cars, and which will be of such form as to closely engage the window sash without binding the same, and which may be made adjustable so that a sufficiently snug fit can be at all times maintained between the frame and the sash, to keep out rain and dirt.

Another object of my invention is to simplify and improve generally the structure and arrangement of railway cars.

One form which my invention may take is shown in the accompanying drawing, wherein Figure 1 is a cross sectional view of a portion of a passenger car body, equipped with my invention; Figs. 2, 3, 4 and 5 are views taken on the lines II—II, III—III, IV—IV, and V—V, respectively, of Fig. 1.

As shown in the drawing, the car body is provided with car lines 6 (only one of which is shown), roof plates 7 and 8, side posts 9, and inner and outer side sheets 10 and 11 that are suitably secured to the posts 9 by rivets or screws. The roof plates 7 and 8 and the car lines 6 are secured to a Z bar or side plate 12 that extends longitudinally of the car. The side posts 9 and plates 10 and 11 are also suitably connected to the Z bar 12, it being understood that a bar 12 will be provided at each side of the car.

In practice, the outer side sheets 10 are riveted to the posts 9, openings being left upon the inner side of the posts to permit of conveniently placing the rivets, after which the inside or finishing plates 11 are placed against the posts, and secured thereto in any suitable manner, as by screws.

The lower edges of the plates 10 are bent outwardly, as indicated at 13, to serve as a protecting hood for shielding the windows from rain. A window sill plate 13^a extends across the space between inner and outer plates, and has its ends of reduced width and turned down, as indicated at 14, to fit between the inner and outer plates 10 and 15, the plates 15 being thicker than the plates 11 because of the wear to which they are subjected.

Windows 16 are placed between the posts

9, at suitable height and are arranged to have vertically sliding movement in guides 17, one of which is shown more clearly in Fig. 4, it being understood that a guide is provided for each vertical edge of the window sash. The guide is formed preferably of a strip of sheet metal that is bent along lines extending longitudinally thereof, in such manner as to form a fold 18 adjacent to its outer edge, and a channel 19 adjacent to its inner edge. The guides 17 are secured to the side posts 9 by screws 20, so that it is unnecessary to rivet the window guiding strips to the posts. The screws 20 also extend through angle bars 21 that are tapped to receive screws 22 which extend through the walls of the channel 19 and through the inner edge of a yieldable strip 23, whose outer edge bears against the window sash. Adjustment of the screw 22 will cause the strip 23 to bear against the window sash with a desired degree of pressure, thus holding it against the fold 18, and effectively preventing entry of dirt and rain, when the window is closed. Not only is it possible to conveniently adjust the guides to snugly engage the window sash, without excessive binding, but the guides may be readily removed for replacement and repair.

Curtain housings 24 are mounted against the inside plates 11, and curtain guides 25 are secured to the posts 9 by screws, which also assist in holding the finishing plates 26 against the inner open sides of the posts 9.

I claim as my invention:

1. The combination with a railway car having side posts, of window guides detachably secured to said posts, and means independent of the guide-securing means, for adjusting said guides to fit window frames of various dimension.

2. The combination with a railway car provided with side posts, of window guides fastened to said posts, and means independent of the fastenings, for adjusting the guides to fit windows of various dimensions.

3. Car structure, comprising a car body having side posts, outside sheets secured to said posts, the lower edge of each sheet being bent outwardly and downwardly to serve as a shield for a window, and window guides secured to adjacent faces of two posts, below said lower edges of the said sheets.

4. Window guide structure, comprising a

- plate having a flange adjacent to one edge thereof, means for attaching the plate to a supporting structure, a flange disposed adjacent to the other edge of said plate and 5 extending in substantial parallelism therewith, and means engaging the last named flange and said plate for shifting the position of said flange with respect to the first named flange.
10. 5. Window guide structure, comprising a plate having a fold formed adjacent to one edge, and said edge extending past the body of the plate, in a direction opposite to that in which the fold extends, an offset portion 15 in said plate, adjacent to the opposite edge thereof, a second plate having one edge extending into said offset portion, and its other edge disposed opposite to said fold, and a screw extending through the second plate 20 and said offset portion for adjustably positioning said plate relative to said fold.
6. Window guide structure, having oppositely disposed flange portions for engaging the sides of a window sash, and means 25 for adjustably positioning said flange portions relative to one another to vary the distance between the same.
7. The combination with a railway car,
- provided with a window opening, of window sash guides in said opening, each of said guides being provided with a yieldable flange member and a second flange member between which the window sash may slide, one of said flange members being adjustable with respect to the other. 30
8. The combination with a railway car, provided with a window opening, of a guide member for window sash, a second guide member spaced transversely of the first named guide member, so that a window sash 40 may fit therebetween, and means for adjustably supporting the second named guide member upon the first mentioned member.
9. The combination with a railway car, having a window opening, of a guide member 45 for window sash, having a pair of outwardly extending flange-like portions for engaging a supporting structure, and an inwardly extending flange portion for engaging one side of a window sash, and means for yieldably holding a window sash against the last named flange portion. 50

In testimony whereof I the said ANDREW CHRISTIANSON have hereunto set my hand.

ANDREW CHRISTIANSON.
